COILING MECHANISM

Harold K. Beach, Cranford, N. J., assignor to
 Phelps Dodge Copper Products Corporation,
 New York, N. Y., a corporation of Delaware

Application February 15, 1938, Serial No. 190,557

11 Claims. (Cl. 242—84)

My invention relates to coil winding devices for use in the coiling of wire and/or rods of unlimited lengths and more particularly to a device which provides a means for the easy removal of a finished coil of wire without the necessity of interrupting the progress of the wire and/or rod or the stopping of the machine, thereby saving the time so lost, and has for its object the production of a machine for continuously forming coils of rod or wire from an indefinitely large source of supply, with the coils of any desired weight, permitting the removal of the coils from the coiling mechanism without interruption of the feed of the wire or rod to the coiling mechanism.

My invention consists in mounting a drum on a rotating spindle, which is a part of a flyer of a standard coil forming machine, holding this drum against rotation by a plurality of movable fingers 20 and laying the coil about its periphery while supporting the coil on these movable fingers.

When the weight of the coil reaches a predetermined amount or has received a predetermined length of wire, these fingers are momentarily withdrawn and the coil is lowered out of position, giving way to the succeeding coil which is then coiled and formed upon the fingers like the first coil.

The foregoing and other features of my invention will now be described in connection with the accompanying four sheets of drawings forming part of this specification in which I have represented my device in its preferred form after which I shall point out in the claims those features which I believe to be new and of my own invention.

In the drawings:

Figure 1 is a side elevation of my coil winder in its preferred form in part section.

Figure 2 is a front elevation thereof in part section.

Figure 3 is a top view.

Figure 4 is a section through the drum along the line 4—4, Figure 2.

Figures 5, 6, 7, 8 and 9 are diagrammatic views, showing the relative position of the two sets of fingers during the completion of a coil and its removal from the drum.

Figure 10 is a detail of the cam operated valve controlling the air cylinder operating the set of fingers having radial movement with respect to the drum.

Figure 11 is a detail of the cam operated valve controlling the air cylinder operating the set of

fingers having longitudinal movement with respect to the vertical axis of the drum.

In the carrying out of my invention I employ a drum 20 mounted on shaft 21 which is suspended from a rotating flyer 22. The shaft 21 turns in bearings 23 and 24 provided for the purpose in the drum, which is held against rotation by a plurality of fingers 25. These fingers are pivotally mounted at pivots 26 so that the horizontal portion 27 of the fingers which project toward the drum move radially to and from the drum 20 and engage the notches 28 therein while the fingers are in their normal position. The horizontal members 27 provide a support upon which the coil is formed by the rotation of the flyer 22. While the action of the flyer in coil forming is well known in the art and should not require any further description here, the type shown for purpose of illustration is the pipe type in which the flyer 22 is a pipe mounted to turn in bearings 29 and 30 and rotated through the spur gears 31 and 32, main shaft 33 and pulley 34 from any source of power (not shown).

The wire 72 is fed into the top of the machine and travels through the hollow flyer 22 and is laid in coils about the drum 20 on the finger supports 27.

The fingers 25 are provided with adjustment 35 so that the proper engagement with the drum can be obtained and they may be provided with 30 a spring 36 to take care of any unevenness in the slots.

When the coil is formed by motion of the rotating flyer 22 around the drum 20, it is supported upon the projections 27 of the fingers 25 until a predetermined weight of coil or desired length of strand is had, when the fingers 25 are momentarily withdrawn allowing the coil to drop below the fingers, after which the fingers 25 are returned to their original position.

The fingers 25 are each provided with an enlarged cylindrical hub 37 through which the pivot 26 passes. On the outside periphery of this hub I provide a cam slot 38. Adapted to travel in these slots 38, I provide a plurality of rollers 39, one for each finger 25, mounted on studs 40 to the oscillating ring 41. The rotation of this ring moves the fingers 25 away from and toward the drum 20 as will be readily understood.

The ring 41 is moved by air cylinder 42 which is connected to the oscillating ring 41 through piston rod 43, universal joint 44 and stud 45.

The movement of the ring 41 is through the air cylinder 42, the piston of which is controlled

50

45

55

by a valve 46, (see Figure 10) which is timed by the cam 47 keyed to shaft 48.

In the construction shown I provide a roller 49 mounted on an oscillating lever 50 pivoted at 51. This roller travels on the face of the cam 47 and rocks the lever 52 and valve handle 53 opening and closing the valve 46.

In Figure 11 I show a similar cam operated valve 54 which is controlled by cam 55 also mounted on shaft 48. Cams 47 and 55 are keyed to shaft 48 which is rotated a definite fraction of one revolution by movement of lever 92. Lever 92 connects to shaft 48 through the pawl 93 and ratchet wheel 94. The movement of lever 92 is between two definite positions 92 and 92'. This movement is determined by stop 95 carried by lever 92 engaging notches 96 and 97 in quadrant 98. Pawl 99 prevents shaft 48 from rotating in a reverse direction.

In operation, the operator moves lever 92 from its position 92 to position 92'. As a result, shaft 48 and cams 47 and 55 are rotated a definite fraction of a revolution so that cams 47 and 55 operate valves 46 and 54 in proper sequence. For the next step of the cycle, operator withdraws lever from 92' to 92, and advances it again to 92'.

Cam 47 controls the opening of valve 46 which is piped to cylinder 42 and cam 55 controls the opening of valve 54 which is piped to cylinder 67 so that one complete rotation of the shaft 48 in definite intermittent movements causes the cylinders to actuate the fingers and perform the cycle shown in detail in Figures 5, 6, 7, 8 and 9. The cam 47 controls the valve 46 which actuates cylinder 42 which moves the ring 41 which in turn moves the fingers 47 to and from the engagement with the drum 28 while cam 55 controls the valve 54 which operates cylinder 67 to move fingers 57 up and down.

During the time the fingers 25 are withdrawn from the drum 20, it is held against rotation by a plurality of fingers 57 which move longitudinally with respect to the vertical axis of the drum and in the upper position engage slots 58 in the drum 20. In the arrangement shown these fingers 57 are attached to a plunger 59. The plunger is mounted for vertical movement in guides 60 and raised and lowered by the motion of the lever 61 pivoted at 62. In the arrangement as illustrated the lever 61 is provided with a slot 63 in which a roller or stud 64 moves. This stud is attached to a rotating disk 65 and is revolved through a train of gears 66 by the reciprocal movement of the piston in the air cylinder 67 converted by the pawl and ratchet 68.

This cylinder 67 is controlled by the valve 54 herebefore described. When the coil is to be removed the piston head 69 picks up the stripper plate 70 guided by guide pins 71 and raises it to the position shown in Figure 7 so that the coil may then rest on the plate 70, upon the withdrawal of the fingers 25 as shown. The plate 70 is then withdrawn into position shown in Figures 8 and 9 while the fingers 25 immediately return to the original position as shown ready to receive the loops of wire of the next coil.

After the fingers 25 return to their normal position shown in Figure 9 the plunger 59 continues downward to position to that shown in Figure 5 leaving the machine clear for the removal of the coil after manually severing the strand of wire.

From the above description it will be readily understood that the movements of the fingers 25 and 57 are interlocked through the control of the cylinders by the cams 47 and 55 mounted

with proper relation to each other on shaft 48 and actuated by lever mechanism 56.

While I have shown a pipe type of flyer I may use any of the standard types of flyers in which the rod or wire may be led around sheaves or pins instead of through the pipe 22 as shown. My invention is supporting a spindle from a rotary flyer of any type and the mounting of a drum upon the spindle in such a way that the coil of wire may be removed without stopping the machine or the continuous feed of the wire.

In the mounting of my spindle 21 from the flyer 22 I show a balancing arm 73 of similar construction to the flyer tube 22 which is provided to give dynamic balance to the rapidly revolving part. From the flyer tube 22 and this arm 73 I suspend two disks 74 and 75 to which the spindle 21 is securely fastened so that it revolves with the rotating flyer.

While I have shown the actuating and interlocking mechanism in its preferred form for simplicity of operation, I do not wish to limit myself to that specific means for operating the two sets of fingers to and from engagement with the drum. It will be readily understood that I may employ an electric system of operation through motor driven shafts and/or solenoids interlocked by interlocked switches instead of the air cylinders, or I may directly connect two sets of fingers by mechanical transmission such as shafts, gears or cams, as is well known to the art of machine design.

I wish it distinctly understood that my coil winder herein described and illustrated is in the form in which I desire to construct it and that changes or variations may be made as may be convenient or desirable without departing from the salient features of my invention and I therefore intend the following claims to cover such modifications as naturally fall within the lines of my invention.

I claim:

1. An apparatus for continuously forming wire and/or rods into coils, comprising a rotating flyer to form the wire and/or rod into a coil, a drum loosely mounted in relation thereto to receive the coil, two sets of fingers mounted for movement to and from the drum, means carried by the drum for engagement by the fingers to hold the drum against rotation, means to control the relative motion of the fingers to permit the removal of the coil without movement of the drum.

2. An apparatus for continuously forming wire and/or rods into coils, comprising in combination, a rotating flyer, a stationary drum suspended therefrom, two sets of fingers mounted for movement to and from the drum to alternately engage and disengage the drum, means to control the movement of these fingers in sequence whereby a coil laid upon the drum by the rotating flyer can be removed from the drum without rotating the drum.

3. The device of claim 2 with the addition of means to interlock the fingers to secure proper sequence of movements.

4. An apparatus for continuously forming wire and/or rods into coils, comprising a rotating flyer, a drum loosely mounted in relation thereto to receive the coil, two sets of fingers mounted for alternate intermittent movement to and from the said drum whereby one set of fingers is always in engagement with the drum to hold the drum against rotation.

5. An apparatus for continuously forming wire

- and/or rods into coils, comprising means to form the wire and/or rod into a coil, a drum loosely mounted in relation thereto to receive the coil, a plurality of fingers mounted for radial movement to and from engagement with the drum, a plurality of fingers mounted for longitudinal movement to and from the drum, means to control the relative motion of the fingers so that one set of fingers is always in engagement with the drum to prevent rotation thereof.
5. The device of claim 5 with the addition that the radial fingers are adjustable in their separate movement.
6. The device of claim 5 with the addition that the sequence of movement of the interlock is so timed to permit the removal of the coil without movement of the drum.
7. The device of claim 5 with the addition that the sequence of movement of the interlock is so timed to permit the removal of the coil without movement of the drum.
8. An apparatus for continuously forming wire and/or rods into coils comprising means to form the wire and/or rod into a coil, a drum mounted to rotate about a shaft supported by the coil forming means to receive the coil, a plurality of fingers mounted for intermittent engagement with the drum, a second set of fingers mounted for 20 intermittent engagement with the drum, means
- 25

to interlock these intermittent motions whereby at least one set of fingers is engaged with the drum to prevent rotation of the drum.

9. The device of claim 8 with the addition that one set of fingers have adjustable means to regulate the engagement with the drum.

10. The device of claim 8 with the addition that the sequence of movement of the interlock is so timed to permit the removal of the coil without movement of the drum.

11. An apparatus for continuously forming wire and/or rods into coils comprising means to form the wire and/or rod into a coil, a drum loosely mounted in relation thereto, to receive the coil, means mounted for intermittent movement to and from engagement with the drum to support the coil in position on the drum while being formed, a secondary means mounted for intermittent movement to and from engagement with the drum to receive the finished coil, means to interlock these intermittent motions whereby at least one of the first two named means is engaged with the drum to prevent rotation of the drum.

HAROLD K. BEACH. 25
